UNITED STATES PATENT OFFICE

WILLIAM BEEHLER, OF BALTIMORE, MARYLAND

AUTOMOBILE UMBRELLA HOLDER

Application filed December 29, 1928. Serial No. 329,254.

My invention relates to means for advantageously locating or detachably securing an umbrella in an automobile, so that the umbrella is instantly available for use in case of rain.

Heretofore the carrying of umbrellas in motor cars has been discouraged because an ordinary umbrella placed loosely in any part of the car body is in the way of passengers, will not maintain an upright position because of the car-body motions, and will usually fall to the floor where it is liable to damage by the shoes of passengers; and the umbrella fabric is also chafed or ruined by friction, in almost any position in which it may be located. While various holding devices supposedly suitable for this purpose have been proposed, all of such known to me have been defective because of inconvenient location, complication and unjustifiable cost, and other reasons, including especially failure to securely hold the umbrella in such position or such manner that it is free from pounding or chafing against the holder itself or parts of the car-body structure; for these reasons such devices have had practically no commercial usage.

By long familiarity with the manufacture, sale and use of umbrellas, and study and experiments directed to overcoming the difficulties or disadvantages above briefly referred to, and to making the carrying of umbrellas in "cars" convenient and practical, I have produced holding devices, and have so located them in or combined them with the car-body structure (as herein disclosed), that the umbrella is in an out-of-the-way position where it does not hamper the movements of occupants and is not subject to injury by any of their movements, but is at the same time easily and immediately accessible for use; the umbrella is readily detachable from the holder, but when placed therein is securely or firmly held, in such manner that it is free from chafing or other injury by contact with parts of the holder itself or other objects; and in some forms or adaptations of the invention, the umbrella is additionally protected by an easily operated cover, which also protects the body upholstery and the

occupants from moisture, when the umbrella is put away "wet".

The importance of so supporting the umbrella that abrasion of the fabric by rattling or "pounding" movements is prevented, will be realized when it is understood that the usual metal frame including the ribs weighs about 1 lb.; that when the vehicle is moving the body is always in more or less violent motion, and if not properly positioned or supported, the umbrella frame acts as a hammer to press, pound or rub the fabric against any adjacent object, which is practically an anvil for the frame-hammer action; if any such abrasive action is permitted, the fabric is quickly chafed or worn through, and in a short time will be completely ruined. This I have proved by tests, and it is also shown to be true by the old practice of carrying unprotected inner-tubes of tires in the tool box; in such cases the tube was always abraided and perforated by contact with other objects, and after such experience the necessity was apparent for protecting the tube with a heavy cover, if carried loosely in the tool box or elsewhere.

I have also found that a very advantageous location in an automobile for an umbrella holder, is in an upper part of the body, and so positioned that the umbrella is held horizontally; such a location may be on the rear wall of the body, above the rear window, or more desirably, as herein disclosed, directly above the windshield, for reasons, and with advantages stated below.

The term "umbrella" as here used is to be understood as including "parasol", although the greatest utility of the invention is in providing for the proper carrying in vehicles of true umbrellas.

The characteristics and advantages of the invention are further sufficiently explained in connection with the following detail description of the accompanying drawings, which show certain representative embodiments; after considering these examples, skilled persons will understand that many variations may be made without departing from the principles disclosed, and I contemplate the employment of any structures or ar-

rangements that are properly within the scope of the appended claims.

Fig. 1 is a perspective view of one typical motor vehicle, with an umbrella holder combined therewith in one preferred position, and embodying the invention in one form.

Fig. 2 is a front elevation of the holder, with its cover or case open, and with the umbrella in position.

10 Fig. 3 is a similar view, with the umbrella removed.

Fig. 4 is a section at 4—4, Fig. 2.

Fig. 5 is a view of one end of a holder generally similar to Figs. 1 to 4, but modified 15 in respect to the holding clip, which in this example is longitudinally adjustable.

Fig. 6 shows a complete holder, the cover of which is provided with a fastener of the continuous, "rip-strip" type.

20 Fig. 7 is a perspective view of a somewhat modified construction, adapted to cooperate with the holder, or other holders such as herein shown.

Fig. 8 is a front elevation of another form 25 of holder, with an umbrella supported therein in a different way.

Fig. 9 is a section at 9—9, Fig. 8.

Fig. 10 is a view similar to Fig. 9, but showing another operative position of the 30 clip.

Fig. 11 is a perspective view of another modified form of clip.

Figs. 12 and 13 show other forms of holders.

35 Figures 1 to 4 inclusive show one preferred form of holder H. This includes a frame 1, which may be a narrow, straight flat strip of metal, provided with holes to receive attachment bolts, or screws 2. Clips 3 are secured

40 to the frame strip, as by rivets 4 passing through their base portions 5. The clips proper, 6, are formed by slotting the pieces 5, as at 7, producing separate spring-jaws 8, which are bent to parallel position, at right-angles to strip 1 and base 5. Preferably, 45 portions 7^a of the slots extend into the base portions 5, (Figs. 3 and 5) or past the "corner" produced by bending the jaws, and into the main strip 1 (Fig. 7), thus insuring ample

50 flexibility of spring-action. The ends of the jaws are beveled, as at 9, and each of these beveled faces leads to a part-round socket formation 10. The socket formations of each pair of jaws provide a complete socket to 55 positively but releasably grip a portion of the rod 11 of an umbrella U. Thus one of the clips receives the tip or ferrule portion of the rod, 11^a, Fig. 2, and the other clip receives a portion of the rod adjacent the

60 lower end of the handle 12, or between the handle and the tips 13 of the ribs. The umbrella may in some cases, and as here shown, be slightly modified to facilitate cooperation with the clip; that is, the rod and handle are 65 so dimensioned or arranged as to leave a

small space between the rib tips and the adjacent end of the handle, sufficient to receive the relatively thin clip jaws without displacement of the rib ends. Otherwise, as in case of an ordinary or unmodified umbrella, 70 in which the rib ends are located close to the handle end, the rib tips may be crowded to one side, sufficiently to permit insertion of the rod portion in the clip-socket. Since men's umbrellas at the present time are practically all of standardized dimensions, especially as to rib-length, and since the principal utility of an umbrella when carried in a motor car is to provide the greatest possible protection from rain, and decorative 80 appearance such as is found in women's umbrellas or others of special types or dimensions, is unimportant, the clips may be spaced apart a distance slightly greater than the rib-length of such a standard umbrella, and 85 may be permanently secured in position, and will still accommodate umbrellas of considerably varying rib or rod-length, since the length of the tip or ferrule portion 11^a is such that the corresponding clip may engage 90 it at different relative portions of its length.

If necessary or desirable, however, one or both clips may be made longitudinally adjustable, to accommodate varying umbrella dimensions, as shown in Fig. 5, where the frame-strip 1 is provided with a longitudinal slot 1^a, and the clip-base 5 is slidably secured by upset rivets 4^a passing through the slot. The fit of the rivets may be tight enough to frictionally retain the clip in adjusted position; however, even if loosely connected, the clip or clips are retained in proper positions by engagement with the umbrella rod, when the umbrella has been properly inserted in them.

100 The rolled umbrella is easily inserted in the holder by applying the stated rod portions to the socket entrances provided by the beveled clip-jaw edges 9; pressure causes the jaws to resiliently spread, and the rod 110 portions snap into the sockets; the umbrella is then firmly and in effect positively held, without possibility of movement in relation to the holder, and with its fabric (preferably, 115 as shown in Fig. 4) out of contact with the frame or any other portion of the holder, and immune from abrasion when the holder is properly located and secured in the car body, as sufficiently referred to below.

120 The holder may be used without a cover, but a cover such as C is desirable, and preferred in many cases. This cover is of generally tubular form, made in one or more pieces or gores, and is preferably designed to envelop the holder frame and the umbrella 125 and to fit the latter closely, in order to avoid chafing. The cover has at one (the front) side a longitudinal opening, as defined by the edges 15, long enough to permit 130 easy insertion of the umbrella, and the over-

all dimension of the cover is slightly greater than the length of a standard umbrella. The frame 1 desirably has extensions 16, beyond the clips, of sufficient length to properly 5 "spread" the cover longitudinally.

Any known or suitable type of quickly-operated fasteners may be provided for the cover opening, such as the snap fasteners 17 of Figs. 1 to 4; or preferably, in many cases, 10 a fastener 18 of the continuous, "rip-lock" type, as shown in Fig. 6.

The material of the cover may vary. In some cases it may be substantially waterproof, as of imitation leather, water-proofed 15 canvas, etc. But preferably it is of non-water proof material, which is substantially porous, but thick enough to absorb all the "drip" from the rolled umbrella, if put away wet, and to permit drying of the umbrella by 20 evaporation through the cover, rapidly enough to avoid injury to the umbrella fabric. It is also desirable in many cases to use a material which harmonizes, or is identical, with the car upholstery. Thus, the cover 25 may be of velour, or other material frequently used for motor-car upholstery, and in such cases can usually be made very inexpensively of waste pieces of the upholstery material.

20 The holder may be secured in any suitable position within the car body, including the locations mentioned early above. A preferred location in many cases is that shown in Fig. 1, where the holder is secured by (bolts 25 or) screws 2, passing through frame 1 and the cover, to the vertical wall 20 above the windshield 21 of any "closed" car, or any car having a "standing" roof. Since the one regular and necessary occupant of the car is 30 the driver, and he will therefore use it more often than any other passenger, the umbrella is thus made most immediately and conveniently accessible to him. Especially when placed in a taxicab, as here shown, the umbrella is convenient to the driver, for his use in escorting passengers from car to house door, and also always in his view, so that chance of loss of the umbrella is minimized.

Fig. 8 shows another modified umbrella U, 35 in which the rod has short portions 25 projecting at the tip and handle ends, and provided at their ends with circular flanges or buttons 26. This umbrella will cooperate with the holder H above described, or with 40 the simplified holder H² of Fig. 7, in which the clips 8 are made integral with frame strip 1. The umbrella rod and button formations are designed to receive the holder jaws in an obvious way, the rod members 25 snapping 45 into the holder sockets, as in the previous example; and the buttons 26 and adjacent handle or tip formations prevent longitudinal movement of the umbrella. This result will also be produced if the rod and button arrangement such as 25-26 is provided at only

one end, with the ordinary tip or ferrule construction at the other end of the umbrella.

Figs. 8, 9 and 10 show another modified holder, or especially a modified clip at one end thereof, to cooperate with an ordinary 70 or standard umbrella. Here the clip 5^a includes a fixed jaw 30, which may be integral with the frame strip, and bent perpendicularly thereto, and another jaw 31, pivotally mounted at 32, with a spring 33 tending to 75 move jaw 31 to a clamping position. The jaws have inner concave or arcuate edge formations 34, designed to receive and grip a relatively large portion of the umbrella, such as the group of rib-tips adjacent the handle, 80 or the handle 12, as shown in Figs. 8 and 9. The other clip may be of any of the forms above described. Evidently this holder avoids necessity for any modification of the umbrella. The jaws 30 and 31 also desirably 85 have on their inward faces, half-round socket formations 35 which will grip the rod 11 of an umbrella, as shown in Fig. 10, if such a rod portion is available; thus this clip may be used alternatively, to grip a handle, or other 90 large-diametered portion, or a small diametered portion, such as the tip, of the umbrella. In some cases the clip of Figs. 9 and 10 may be used at each end of the holder.

Fig. 11 shows another modified clip, including a fixed jaw 40 having a socket 41, and a "flat" spring 42 secured to frame strip 1, suitably bent and provided with a notch or socket formation 43 to cooperate with socket 41 and retain a rod or other portion 100 of the umbrella. The ends of the spring or clip, and of jaw 40, are rounded, or beveled at 40^a, to facilitate insertion of the umbrella rod.

In some cases, as, for example, when the 105 holder is to be installed in the motor car by the manufacturer the clips need not be connected by a frame strip, but may be individually secured to a suitable part of the body (such as wall portion 20, Fig. 7, for example) 110 in properly spaced relation, and with the cover properly located about the clips and by them secured to the body wall.

Figs. 12 and 13 show holders of loop form. The clip or holder 50 of Fig. 12 is designed to 115 accommodate the handle, or other part of a rolled umbrella, and clip 51 of Fig. 13, to receive the tip. These loops absolutely prevent displacement of the umbrella. They may be combined with a base-strip as shown 120 in Fig. 3, or integral therewith as in Fig. 7, or secured individually in position in the car-body.

I claim:

1. An umbrella holder for automobiles comprising an enclosure of flexible sheet material having a front opening with detachable fastening means and adapted to snugly receive and enclose an umbrella, and means therein for positively and detachably engag- 125
130

ing portions of the umbrella and preventing chafing of the umbrella cover upon the enclosure and for securing the enclosure to the automobile.

- 5 2. An umbrella holder for automobiles comprising an enclosure of flexible sheet material having a front opening with detachable fastening means and adapted to snugly receive and enclose an umbrella, and clips 10 within the enclosure for positively and detachably engaging portions of the umbrella rod and means mounting said clip and securing the enclosure to the automobile.

3. An umbrella holder for automobiles 15 comprising an enclosure of flexible sheet material having a front opening with detachable fastening means and adapted to snugly receive and enclose an umbrella, and within the enclosure, a frame strip provided with 20 means for positively and detachably engaging portions of the umbrella and for securing the enclosure to the automobile.

4. An umbrella holder for automobiles 25 comprising an enclosure of flexible sheet material having a front opening with detachable fastening means and adapted to snugly receive and enclose an umbrella, and within the enclosure a frame strip provided with 30 means for positively and detachably engaging portions of the umbrella rod and for securing the enclosure to the automobile.

5. An umbrella holder for automobiles 35 comprising an enclosure of flexible sheet material having a front opening with detachable fastening means and adapted to snugly receive and enclose an umbrella, and a frame strip within the enclosure, and spaced spring 40 clips thereon adapted to positively and detachably engage portions of an umbrella rod.

6. An umbrella holder for automobiles 45 comprising an enclosure of flexible sheet material having a front opening with detachable fastening means and adapted to snugly receive and enclose an umbrella, and within the enclosure a frame strip adapted for connection to a body portion of an automobile to secure the enclosure thereto and provided with means for positively and detachably 50 engaging portions of the umbrella and holding it without chafing against the enclosure.

7. An umbrella holder for automobiles 55 comprising an enclosure of flexible sheet material having a front opening and slidable fastening means therefor, a frame strip having spaced slots securing the enclosure to the automobile, and umbrella holding clips having means extending within the slots for longitudinal adjustment therewithin.

- 60 In testimony whereof I have signed this specification this 5th day of November, 1928.

WILLIAM BEEHLER.
